UNITED STATES PATENT OFFICE

126,718

DESIGN FOR AN ADENOTOME

Martha R. Grieshaber, Chicago, Ill.

Application May 23, 1940, Serial No. 92,540

Term of patent 14 years

To all whom it may concern:

Be it known that I, Martha R. Grieshaber, a citizen of the United States, residing at Chicago, in the county of Cook and State of Illinois, have invented a new, original, and ornamental Design for Adenotomes, of which the following is a specification, reference being had to the accompanying drawing, forming a part thereof.

In the drawing:

Figure 2 is a side elevational view thereof;
shown in Figures 1, 2 and 3.

I claim:

The ornamental design for an adenotome, substantially as shown.

MARTHA R. GRIESHABER.
